Frazee & Richards,
ATTORNEYS

UNITED STATES PATENT OFFICE.

ANDREW L. HATFIELD, OF HILLSIDE, NEW JERSEY, ASSIGNOR TO THE STRONG MACHINERY & SUPPLY CO., A CORPORATION OF NEW YORK.

GAGE-GLASS GUARD.

1,354,296.

Specification of Letters Patent. Patented Sept. 28, 1920.

Application filed June 6, 1919. Serial No. 302,211.

To all whom it may concern:

Be it known that I, ANDREW L. HATFIELD, a citizen of the United States, residing at Hillside, in the county of Union and State of New Jersey, have invented certain new and useful Improvements in Gage-Glass Guards; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15. The present invention has reference, generally, to improvements in protecting devices for steam boiler water gages and the like; and the invention relates, more particularly, to a novel construction of protecting means adapted to be arranged with and to inclose the glass bodies of water gages.

20. The invention has for its principal object to provide a very simple, cheap and easily applied protecting device for the purposes above mentioned, which is easily adapted to inclose the glass body of a water gage, both to guard the same against exteriorly originating accidental blows, as well as against scattering of fragments of the glass body should the same burst from internal causes, and principally for the latter purpose.

25. Other objects of the present invention, not at this time more particularly enumerated, will be clearly understood from the following detailed description of the same.

30. With the various objects of the present invention in view, the same consists, primarily, in the novel construction of steam boiler water gage guard hereinafter set forth, and, 40. the invention consists, furthermore, in the several novel arrangements and combinations of the various devices and parts, as well as in the details of construction of the same, all of which will be more fully described in the following specification, and then finally embodied in the claims appended thereto.

35. The invention is clearly illustrated in the accompanying drawings, in which:—

45. 50. Figure 1 is a front elevation of a steam boiler water gage glass provided with the novel protecting guard made according to and embodying the principles of the present invention.

55. Fig. 2 is a vertical longitudinal section

taken on line 2—2 in said Fig. 1, the gage glass being shown in elevation.

Fig. 3 is a similar vertical longitudinal section, but showing the manipulation of the protecting guard when placing the gage 60 glass into the supporting fittings therefor.

Fig. 4 is a detail rear side elevation of a portion of the protecting guard assembled with the gage glass.

Fig. 5 is a detail horizontal section taken 65 on line 5—5 in said Fig. 2.

Similar characters of reference are employed in all of the hereinabove described views to indicate corresponding parts.

Referring now to said drawings, the reference character 1 indicates an upper fitting or socket member for connection with a steam boiler, or the like, (not shown), and the reference character 2 indicates a lower fitting or socket member for like connection 70 with said steam boiler. Each socket member or fitting 1 and 2 is provided with an exteriorly threaded stuffing-box neck 3, having a cylindrical opening 4 for the reception of the ends of the tubular gage glass 5. An 80 internally threaded cap or nut 6, having a central opening 7 in the body thereof, to permit an end of the gage glass 5 to extend therethrough, screws upon each stuffing box neck 3, to hold under expanded pressure and 85 in tightly embracing relation to the ends of the gage glass a suitable packing 8, adapted to thus form leak tight joints between the supporting fittings and the respective ends of said gage glass inserted therein. 90

The novel protecting guard comprises a body portion 9 adapted to surround the gage glass and so constructed as to provide a substantial area of interstices through which the gage glass and its water content may 95 be readily seen. The major intermediate part of said body portion 9 is preferably maintained against longitudinal contraction or expansion, while its end portions 10 are formed or constructed to be readily contracted longitudinally, so that the same will yield to a loosening or unscrewing movement of the caps or nuts 6 from the fittings 1 and 2, when either applying or removing a gage glass to or from said fittings. 100 105

Preferably I construct said body portion 9 and its end portions 10 of spring wire coiled into spirally convoluted form to embrace the gage glass throughout its exposed longitudinal extent, thus providing between the 110

convolutions suitably disposed open spaces or interstices 11, through which the gage glass and its contents may be easily viewed.

Preferrably the diameter of the spirally convoluted body and its yieldable end portions is slightly greater than the diameter of the gage glass to be inclosed thereby. In order to retain the main intermediate part of said spirally convoluted body against longitudinal contraction, there is provided a rigid longitudinally extending bracing strip 12, which is disposed within the spirally convoluted body against the inner side thereof, and to which certain longitudinally spaced convolutions of the body are rigidly secured by suitable means, such for example, as by a mechanical coupling, solder, welding, brazing, or any other desired means.

When it is desired to use a mechanical coupling, I have illustrated in the drawings a very simple and effective construction which proves quite satisfactory. This mechanical coupling comprises a tongue or lug 13 struck out from the body of the bracing strip 12, and then bent outwardly, over and around an adjacent convolution of the body, to thereby secure the latter to the bracing strip, so that the intermediate portion of said body between such couplings is securely retained against longitudinal contraction.

Those portions of the spirally convoluted body which project beyond the outer couplings, to wit, the end portions 10, are free to yield to longitudinal contraction or compression, as will be clearly understood, thus providing at each end of the guard a longitudinally compressible portion subject to sufficient contraction, or reduction in length, as will easily permit the caps or nuts 6 to be unscrewed from the fittings 1 and 2, as is clearly illustrated in Fig. 3 of the drawings.

Secured to the extremity of each yieldable end portion 10 of the spirally convoluted body is a ferrule 14, provided at its outer end with an inwardly projecting annular flange 15, against which the respective extremities of said end portions 10 abut, and to which said extremities are secured by means of solder, or by any other suitable fastening means.

When the guard device thus constructed is properly assembled in embracing or inclosing relation to the gage glass, and the latter is secured between the fittings 1 and 2, the compressible end portions 10, by virtue of their tendency to resume normal longitudinal extension after compression, press

the ferrules 14 securely against the respective caps or nuts 6 of the fittings 1 and 2, and thus hold the guard in completely enveloping relation to the exposed portion of the gage glass. Preferably the bracing strip 12 is so located as to be positioned behind the gage glass, and said bracing strip may be painted or otherwise colored, so that the same when viewed through the water in the gage glass will seemingly impart its color to the water, thus rendering the level of said water more clearly visible. I am aware that colored rods and strips have been heretofore employed for this purpose, and consequently I make no special claim in this connection, except to point out that the bracing strip 12 of my device, aside from its more important mechanical function, is well adapted for such purpose.

I am aware that some changes may be made in the arrangements and combinations of the various devices and parts as well as in the details of the construction of the same, without departing from the scope of my invention as set forth in the foregoing specification and as defined in the appended claims. Hence, I do not limit my invention to the exact arrangements and combinations of the devices and parts as described in said specification, nor do I confine myself to the exact details of the construction of the said parts as illustrated in the accompanying drawings.

I claim:

1. A gage glass guard comprising an enveloping spirally convoluted body having longitudinally contractible end portions, and a rigid bracing strip extending through said body to which the intermediate portion of the latter is secured to retain the same against longitudinal contraction.

2. A gage glass guard comprising an enveloping spirally convoluted body having longitudinally contractible end portions, a rigid bracing strip extending through said body to which the intermediate portion of the latter is secured to retain the same against longitudinal contraction, and ferrules connected with the extremities of said contractible end portions.

In testimony, that I claim the invention set forth above I have hereunto set my hand this 15th day of April, 1919.

ANDREW L. HATFIELD.
